CLAIM

The ornamental design for a bottle, as shown and de-
scribed.

DESCRIPTION

FIG. 1 is a side elevational view of a bottle showing my
new design, the opposite side being a mirror image;

FIG. 2 is a rear elevational view thereof;

FIG. 3 is a bottom plan view thereof;

FIG. 4 is a front elevational view thereof; and

FIG. 5 is a top plan view thereof.

The stippling in the drawings denotes a contrasting
color.
